US00D913737S

(12) **United States Design Patent** (10) **Patent No.:** **US D913,737 S**
(45) **Date of Patent:** **** Mar. 23, 2021**

(54) **TABLE**

- (71) Applicant: **Apple Inc.**, Cupertino, CA (US)
(72) Inventors: **Charles A. Schwalbach**, Menlo Park, CA (US); **David Samuel Kumka**, San Francisco, CA (US); **Russell John Kaaihue Heirakuji**, Cupertino, CA (US); **Carly Lynn Marasco**, Los Gatos, CA (US); **Frank Craig Thaler**, Santa Cruz, CA (US)
(73) Assignee: **Apple Inc.**, Cupertino, CA (US)
(**) Term: **15 Years**
(21) Appl. No.: **29/670,426**
(22) Filed: **Nov. 15, 2018**

Related U.S. Application Data

- (63) Continuation of application No. 29/618,445, filed on Sep. 21, 2017, now Pat. No. Des. 833,789, which is a continuation of application No. 29/586,953, filed on Dec. 8, 2016, now Pat. No. Des. 799,250, which is a continuation of application No. 29/516,911, filed on Feb. 6, 2015, now Pat. No. Des. 773,868.

CLAIM

The ornamental design for a table, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top front perspective view of a table showing the claimed design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines in the Figures show portions of the table that form no part of the claimed design.

**1 Claim, 4 Drawing Sheets
(2 of 4 Drawing Sheet(s) Filed in Color)**
